UNITED STATES PATENT OFFICE.

JOHN ALFRED FULLILOVE, OF MARKET HARBOROUGH, ENGLAND.

MACHINE FOR CASTING BOXES AND OTHER HOLLOW METAL ARTICLES.

Application filed August 1, 1925, Serial No. 47,503, and in Great Britain August 6, 1924.

This invention relates to a machine for casting boxes or other such hollow articles from hard lead or the like material.

The difficulty of casting boxes such as would be useful as containers for accumulator plates as well as for other purposes arises from the fact that the walls of said boxes are necessarily thin and in order to obtain sufficiently homogeneous castings the metal must be rapidly distributed throughout the mould in a fluid state and then caused to cool rapidly in the mould.

In addition the mould must be of such a construction as to permit of its being readily opened to enable the cast article to be withdrawn.

In order to effect the desired objects I provide a mould consisting of two separable water cooled parts and a withdrawable water cooled central core and I provide means for injecting the metal into the mould suddenly under pressure.

In the accompanying drawings I have illustrated more or less diagrammatically a means for accomplishing the objects of my invention.

In these drawings Fig. 1 is a plan view of a mould for casting rectangular boxes,

Fig. 2 is an end elevation thereof,

Fig. 3 is a side elevation thereof, and

Fig. 4 is a diagrammatic side view of the complete apparatus.

Referring to these drawings the numeral 1 designates the mould bed plate which has a mould core 2 mounted to slide in the direction of the arrow A. This mould core is also capable of swivelling on the pivot 3 when the core is in its withdrawn position shown in Fig. 1. The mould is constructed in two similar parts 4 and 4^a which are slideable upon the bed 1 in directions at right angles to the arrow A. The bedplate 1 is provided with a nozzle orifice 5 which is connected with a supply of molten metal which is delivered to it under pressure as will hereafter appear. The mould and its core are so arranged that a vertical plane passing through the orifice 5 will bisect the angle formed by the adjacent walls of the box so that there will be an equal tendency for the metal to flow in both directions. This is an important consideration in practice.

Both the mould parts 4 and 4^a and the mould core 2 are water cooled and in so far as these mould parts and core are movable

it is necessary to provide a system of flexible pipes, the general system of which will be understood from Fig. 4. Upon referring to this figure it will be seen that cooling water from a suitable source of supply passes by way of the pipes 6, 7, 8 and 9 to the mould core 2, which is hollow, flexible connections such as short lengths of rigid pipes connected by flexible couplings being provided at 7^a and 8^a. The cooling water passes from the mould core by way of the pipes 10 and 11 similarly provided with flexible joints 10^a and 11^a to an outlet pipe 12. To the jackets of the mould parts the water passes by way of the pipes 6, 13, 14 and 15, the joints at 14^a and 15^a being flexible and after circulating through the mould jackets the water passes out to the outlet pipe 12 by way of the pipes 16, 17 and 18 provided with flexible joints 16^a and 17^a as before. A suitable valve, such as 19, may be provided to regulate the water supply.

The numeral 20 designates an air vessel charged to a suitable pressure by means of the pump or compressor 21, a gauge 22 being provided to indicate the pressure in the container or vessel 20. Compressed air from this vessel passes to the metal pot or container 23 by way of the pipe line 24 in which a stop valve 25 and a two-way cock 26 is provided. A pipe or conduit 27 depends from the metal orifice or nozzle 5 some way beneath the surface of the metal in the metal pot or container 23 so as to ensure that the metal will be taken from beneath the surface upon which dross and impurities are liable to float.

The operation of the machine is as follows:—The mould core 2 is arranged roughly in position by being pushed in by hand for the greater part of its travel and then finally screwed home by means of the screw 28 formed on the rod 28^a which engages a thread in the fixed member 29. The mould parts 4 and 4^a are then similarly closed on to the core, the parts being first pushed together and then finally tightened one against the other by means of the screws 30 formed on the rods 30^a operating on the stationary screw threaded member 31. The screwing up of the mould parts 4 and 4^a operate automatically to position correctly the mould core and it will be understood that when the parts are adjusted to operate on casting position there will be a space between the mould parts and the core equal to the thick-

ness of the box to be cast. The two-way cock 26 is adjusted to its position for delivering air under pressure to the metal pot or container and the valve 25 is opened. By 5 this means metal under pressure of the compressed air is forced through the orifice 5 into the mould.

The two-way cock 26 is then moved into its second position where the compressed 10 air passes to atmosphere and the pressure on the metal is instantly relieved and the valve 25 is again closed. The metal has now been forced completely through the mould, driving out any air through openings or air vents 32 and 33 in the upper part 15 of the mold provided for the purpose and by reason of the cooled mould the casting immediately sets. The mould parts 4 and 4^a are now separated by first operating the 20 screws 30 and then simply pulling the mould parts away and similarly the mould core 2 is withdrawn by first operating the screws 28 and then pulling the core out until its 25 inner end is clear of obstruction when the core can be turned bodily about its pivot 3. The cast box which is on the core can then be removed and will be found to be a sound homogeneous casting.

It will be found that when the core is just 20 shifted it can be withdrawn easily particularly if the mould parts and core are given a slightly tapering form.

After the mould has been opened and the core withdrawn in the manner before described 35 the cast box attached to a tang or break corresponding to the inlet orifice will remain and can quite easily be detached and finished off by the removal of the tang or break and the projections which have been 40 formed by the passage of metal through the air escape outlets.

It will be seen from the foregoing that 45 the essential conditions to be observed are the provision of comparatively cold mould parts and the sudden injection of the hot molten metal under such pressure in such a way as will cause it to flow rapidly and evenly throughout the mould and then solidify rapidly immediately the metal supply is 50 cut off.

What I claim and desire to secure by Letters Patent is:—

1. A machine for casting boxes and like 55 hollow articles comprising a withdrawable water cooled mould core, separable water cooled mould parts adapted to be closed

upon and to position the core automatically, a reservoir for molten metal under releasable pressure, means for injecting the metal into the mould under sudden pressure in the direction of air vents or outlets in the mould, and means for releasing the pressure substantially as specified. 60

2. A machine for casting boxes or like hollow articles according to claim 1 wherein 65 the mould is so arranged and the metal injection nozzle so positioned that the tendency of the flow of the metal into the mould is substantially equal on both sides of a plane normal to the nozzle. 70

3. A machine for casting boxes and like hollow articles comprising a withdrawable water cooled mould core, separable water cooled mould parts adapted to be closed 75 upon and to position the core automatically, a reservoir for molten metal under releasable pressure, means including a nozzle for injecting the metal into the mould under sudden pressure in the direction of air vents or 80 outlets in the mould, and means for releasing the pressure, said nozzle being located at one of the edges of the box adjacent a corner and said mould being so constructed that a vertical plane passing through the 85 nozzle bisects the angle between the adjacent sides of the box whereby the tendency to flow of the metal is equal on both sides of said plane. 85

4. A machine for casting boxes and other hollow metal articles comprising essentially 90 a water cooled core and mould parts and means for supplying molten metal under controlled air pressure. 95

5. A machine for casting boxes and other hollow metal articles, comprising two mould 95 parts mounted on guides so as to be movable to and from each other, and a movable mould core mounted on guides so as to be movable to and from the mould parts, said mould parts and said core having cooling 100 water receptacles, and a water circulating system consisting of rigid pipes communicating with said water receptacles and flexibly connected to accommodate the movement of the mould parts. 105

6. A machine for casting boxes and other hollow articles in accordance with claim 5, wherein the movable mould core is mounted on a pivot so as to be capable of both a sliding and pivotal movement in the same plane. 110

In witness whereof I affix my signature.
JOHN ALFRED FULLJOLOVE.
